UNITED STATES PATENT OFFICE.

THOMAS M. PRICE AND JOHN W. TILLMAN, OF COOPER, TEXAS.

WIRE CLOTHES-PIN.

1,156,810.

Specification of Letters Patent.

Patented Oct. 12, 1915.

Application filed January 15, 1914. Serial No. 812,291.

To all whom it may concern:

Be it known that we, THOMAS M. PRICE and JOHN W. TILLMAN, citizens of the United States, residing at Cooper, in the county of 5 Delta and State of Texas, have invented certain new and useful Improvements in Wire Clothes-Pins; and we do declare the following to be a full, clear, and exact description of the invention, such as will enable others skilled in the art to which it 10 pertains to make and use the same.

This invention relates to improvements in clothes pins and more particularly to those formed of a single piece of resilient wire.

15 The primary object of the invention is to provide a device of this character whereby a plurality of curved gripping faces are employed in gripping the garment hung on the clothes line.

20 A secondary object is to simplify the structure of devices of this character to such an extent as to render them considerably more practical than numerous articles in this class now on the market.

25 With the above objects in view, the invention resides in certain novel features of construction and combination herein described and claimed and shown in the drawings wherein—

30 Figure 1 is a side view of our improved clothes pin; Fig. 2 is a plan view thereof; Fig. 3 is an end view; and Fig. 4 is a vertical section on the line 4—4 of Fig. 1.

In the accompanying drawings, we have 35 shown our improved clothes pin as formed of a single piece of resilient wire given a plurality of coils at its central portion to produce a central ring 1 which is adapted for slidable engagement with the clothes line

40 C as is usual with devices of this character. Since both free ends of the wire are treated in the same manner, we will describe the various twists and bends in but one end thereof. Each free end of the wire is bent

45 laterally as at 2 and extended in a plane at right angles to the plane of the ring 1 to form an arm 3 which has its free end coiled to produce an eye 4 lying in substantially a horizontal plane, the wire then being bent

50 to form a ring 5 disposed at right angles to the plane of the ring 1, the plane in which said ring 5 lies, being in substantial alignment with the arm 3. It will be noted that the two ends of the ring meet at its upper

55 side, and that one of the free ends thereof

is continued upwardly through the eye 4, is then bent downwardly around the arm 3, and is extended in a vertical plane, diametrically across said ring 5, whereby to form a clamping finger 7, the intermediate portion 60 of said finger being curved inwardly into the ring 5 and coiled as seen at 6, to provide a combined clothes line stop and resilient connection between the two ends of the finger, and the lower end of the latter being 65 curved outwardly and then downwardly as seen at 8. By this formation, the portion of the finger 7 directly beneath the coil 6 is spaced laterally from the plane of the ring 5, as indicated at 9, this space receiving the 70 clothes line C, as most clearly seen in Figs. 3 and 4. It will be noted that the extreme lower end of the finger 7 likewise extends a slight distance into the ring 5. By this construction, the pin may be readily engaged 75 with the clothes line, and the lower end of the finger is allowed to yield outwardly to prevent mutilation of the clothes hanging thereon, this outward movement being allowed by the coil 6 which likewise forms a 80 stop to prevent excessive downward movement of the pin upon the wire.

By reference to the various views of the drawings, it will be seen that the coil 6 projects into the plane of the ring 5 and forms 85 a stop adapted to contact with the garment being clamped upon the line C, while the inwardly curved portion 7 also lies normally within the plane of said ring, thereby forming a line receiving chamber between said stop 6 and member 7. By this construction we produce a resilient finger 9 which is adapted to coact with the ring 5 in holding 90 the garments on the line C in a manner which will be clearly understood.

As clearly shown in Fig. 4, when the pin is in place on the line, the lower surface of the coil 6, the inner side of the flexible finger 9 and the opposite sides of the ring 5 will all coact to securely retain the article hung 100 on said line without danger of tearing or puncturing the fabric.

We lay no claim whatever on the specific construction of the ring 1 since the form shown in the drawings is common in devices of this character and it will be clearly understood that the structure to each side of the ring 1 would operate equally as well with any form of central ring.

Having thus described our invention, what 110

we claim as new and desire to secure by Letters-Patent is:

A clothes pin constructed of a single piece of wire bent to form an upright ring, the 5 end portions of the wire meeting at the top of the ring, one of said portions being there coiled to provide a horizontal eye, and the other end portion being continued upwardly through said eye and then bent downwardly 10 across the center of the ring to form a gripping finger, the latter having its intermediate portion curved into the ring and bent to form an upright coil, said coil acting as a

combined clothes line stop and resilient connection between the two ends of the finger, 15 and the lower end of the latter being curved outwardly to facilitate the engagement of the pin with the line.

In testimony whereof we have hereunto set our hands in presence of two subscribing 20 witnesses.

THOMAS M. PRICE.
JOHN W. TILLMAN.
